UNITED STATES PATENT OFFICE.

OTTO HEINR. CHRISTIAN VOIGT, OF LÜBECK, GERMANY.

LABEL-HOLDER FOR BOTTLES, &c.

SPECIFICATION forming part of Letters Patent No. 694,809, dated March 4, 1902.

Application filed August 7, 1901. Serial No. 71,270. (No model.)

To all whom it may concern:

Be it known that I, OTTO HEINRICH CHRISTIAN VOIGT, residing at Lübeck, in the German Empire, have invented certain new and useful Improvements in Label-Holders for Bottles and the Like, of which the following is a specification.

My present invention relates to a device by means of which labels, tickets, or such like may be attached to bottles for the purpose of their exhibition in shop-windows, and the device is so constructed that it can be easily attached or removed and that the label secured on the bottle itself or any other decorative matter on said bottle is not in any way covered nor the cork and seal injured.

The device consists, essentially, of two arms suitably bent to carry the label or the like and of a ring whose diameter can be adjusted. The device may be constructed of wire or any other suitable material.

In the accompanying drawings, representing my invention, Figure 1 is a perspective view of the device; and Fig. 2 shows its application to a bottle, a label being shown in position.

In the construction shown in the drawings the device consists of a single piece of wire, which is suitably bent into the form shown in Fig. 1. A part of the wire is bent into the form of a ring, as shown at *a*, and this part surrounds the mouth or the upper part of the neck of the bottle, as shown in Fig. 2. The two arms *e* for supporting the label have the same shape and are formed by bending the ends of the wire from which the ring *a* is formed. In order to enable the adjustment of the diameter of the ring *a* so that it may fit various sizes of bottles, are provided the serpentine-shaped bends *d*, which form a part of the ring *a*. The diameter of the ring is

adjusted to suit the particular size of bottle by compressing the ring until the desired diameter is obtained and then placing the part *e* into the corresponding bend of the serpentine part *d*, as shown in Fig. 1. 45

What I claim, and desire to secure by Letters Patent of the United States, is—

1. A label-holder for bottles comprising a ring provided with arms to support the label 50 and bent for a portion of its circumference into a serpentine shape adapted to enable the adjustment of the diameter of the ring, substantially as described and illustrated in the accompanying drawings. 55

2. A label-holder comprising a single strand of wire formed first into a ring, the ends of said wire being then bent upright to form parallel arms for supporting the label, a portion of said ring provided with a number of 60 bends whereby the diameter of the ring may be lessened or enlarged for the purpose and substantially as described.

3. A label-holder for bottles consisting of a single strand of wire one end of which being bent to form a supporting-arm, the opposite end being bent upon itself to form short bends for a portion of its length adapted to engage said supporting-arm, and then bent parallel with the other end of said wire and 70 forming a second supporting-arm, the whole so constructed and arranged that the diameter of the ring may be varied in order to fit bottles of different sizes, substantially as and for the purpose set forth. 75

In testimony whereof I have hereunto set my hand in the presence of two witnesses.

OTTO HEINR. CHRISTIAN VOIGT.
